UNITED STATES PATENT OFFICE.

ARCHIBALD J. MURRAY, OF UNITY, OREGON.

WIRE-GATE FASTENER.

1,212,988.

Specification of Letters Patent. Patented Jan. 16, 1917.

Application filed January 10, 1916. Serial No. 71,256.

To all whom it may concern:

Be it known that I, ARCHIBALD J. MURRAY, a citizen of the United States, residing at Unity, in the county of Baker, State of Oregon, have invented a new and useful 5 Wire-Gate Fastener; and I do hereby declare the following to be a full, clear, and exact description of the invention, such as will enable others skilled in the art to which 10 it appertains to make and use the same.

The present invention relates to a wire gate fastening device, and has for its object to provide a locking lever which embodies novel features of construction where- 15 by a barbed wire or wire net gate may be drawn taut and securely fastened.

Further objects of the invention are to provide a device of this character which is comparatively simple and inexpensive in its 20 construction, which can be used in connection with the conventional forms of wire gates such as must be drawn taut in order to be closed; which can be very easily manipulated, and which admits of the gate 25 being quickly released or locked.

With these and other objects in view, the invention consists in certain novel combinations and arrangements of the parts as will 30 more fully appear as the description proceeds, the novel features thereof being pointed out in the appended claim.

For a full understanding of the invention, reference is to be had to the following description and accompanying drawing, in 35 which:—

Figure 1 is a front elevation of a wire gate provided with a locking lever constructed in accordance with the invention, the said locking lever being shown by full 40 lines in operative position and by dotted lines in the position assumed when being placed in engagement with the gate preparatory to stretching and locking the same. Fig. 2 is a similar view on a larger scale, the 45 locking lever being shown by full lines in operative position, and by dotted lines in the position assumed when not in use. Fig. 3 is a top plan view of the locking device, showing the same in operative position. 50 Fig. 4 is a detail view showing a slight modification.

Corresponding and like parts are referred to in the following description and indicated in all the views of the drawings by the same 55 reference characters.

Referring to the drawings, the numeral

1 designates a wire fence of the conventional construction, 2 a gate post and 3 a latch post, the said posts being arranged on opposite sides of the gate opening. The 59 gate includes the two upright end bars 4 and 5 which are connected by the longitudinally extending wires 6, the end bar 4 being loosely engaged by loops 7 which project from the top and bottom of the gate post 25 64. The lower end of the opposite end bar 5 is adapted to be loosely fitted within a loop 8 at the bottom of the latch post 3, while the upper end of the end bar 5 is provided with a locking loop 9. 70

The locking lever 10 is pivotally mounted at a point spaced from the end thereof upon a pivot bolt 11 which projects from the latch post 3, the projecting end 10^a of the lever being curved or deflected downwardly 75 so as to be disposed at an angle to the body portion of the lever, and terminating in a laterally projecting arm 12. The opposite end of the locking lever terminates in a handle 10^b which is offset laterally so that it 80 will clear the latch post 3 and can be easily grasped by the hands at any position of the lever. A locking hook 13 extends beyond the lever 10 and has the shank thereof pivotally connected at 14 to the said locking 85 lever. This pivot point 14 is on the opposite side of the pivot bolt 11 from the arm 12, both the arm 12 and pivot point 14 being spaced substantially equal distances from the pivot bolt 11. The shank of the locking 90 hook 13 may be offset laterally a slight amount to clear the head of the main pivot bolt 11 as the locking lever is swung about its pivot, although in side elevation the shank of the hook is substantially straight, 95 so that when the end of the hook rests upon the lateral arm 12 the shank thereof is on one side of the pivot bolt 11.

The locking hook 13 is designed to engage the locking loop 9 of the wire gate, and 100 when the locking lever 10 is swung upwardly and forwardly, the hook 13 is moved toward the gate so that it can be readily placed in engagement with the loop 9 while the wires of the gate are loose. The locking 105 lever is then swung rearwardly and downwardly into the position indicated by full lines on Figs. 1 and 2, thereby drawing the locking hook 13 rearwardly so as to stretch the wires of the gate and draw the gate taut. 110 Just before the lever 10 reaches a locking position the shank of the hook 13 will be

brought into alinement with the body of the lever 10, thereby producing a dead center between the pivotal mounting of the locking lever and the pivotal connection of the hook 5 13 thereof. A continued movement of the locking lever swings the hook 13 beyond the dead center and the hook then engages and seats upon the laterally projecting arm 12. The gate is thus locked in a taut condition, 10 and the greater the pull of the gate, the more secure is the locking. The extremity of the laterally projecting arm 12 is provided with an upwardly projecting guard finger 12^b which serves to engage the hook 15 when in a locking position so that it will be impossible for pressure of stock against the gate to move the hook laterally beyond the end of the arm 12 and thereby release the latch. It will be understood that when closing the gate the lower end of the upright bar 5 will be inserted in the loop 8 before the locking hook 13 is caused to engage the loop 9. Wire gates of this character are extensively used on ranches and large estates, 20 and ordinarily the upper end of the upright gate bar is secured to the post by a rope, although when a rope is used it is almost impossible to fasten the gate sufficiently tight to prevent stock from getting through the same, and much time is lost in fastening 25 and unfastening the ropes. With the present device the gate is easily and quickly drawn perfectly taut and securely locked so as to prevent any possibility of stock getting through or unfastening the same. In order to release the fastener, the locking lever may either be forcibly swung downwardly so as to swing the hook member upwardly out of engagement with the loop 9 30 of the gate, or it may be swung upwardly so as to release the tension in the gate before disengaging the hook member from the loop.

A slight modification is shown by Fig. 4, 45 in which the laterally projecting arm 12 of the locking lever is provided with a notched seat 12^b for engagement with the hook 13 when the latter is in locking position. The

hook is thus locked against lateral play upon the arm, thereby relieving the pivot member 50 14 at the end of the hook of a considerable amount of strain. The hook will automatically become seated in the notch 12^b as it is swung beyond the dead center position by the usual manipulations of the locking lever 10.

Having thus described the invention, what I claim as new and desire to secure by Letters Patent, is:—

The herein described wire gate fastener, 60 including a looped keeper adapted to be applied to the end bar of a flexible wire gate, a headed pivot bolt adapted to be applied to the latch post, a locking lever pivotally mounted upon the said pivot bolt and provided at the pivot end thereof with an extension which is arranged at an angle to the body portion of the locking lever, said extension terminating in a laterally projecting arm which is provided at the end thereof 65 with an upwardly extending guard finger, and a hooked member pivotally connected to the locking lever at a point spaced from the pivot bolt and on the opposite side from the extension, said hook member being adapted 70 to engage the looped keeper to draw the gate taut, and the body portion of the hook member being offset outwardly to clear the head of the pivot bolt, the swinging movement of the locking lever incident to tightening the gate bringing the hook member slightly beyond a dead center position and into engagement with the laterally projecting arm, the pull of the gate then holding 75 the hook member in operative position and the upwardly projecting guard finger preventing the hook member from becoming laterally disengaged from the arm.

In testimony whereof I have signed my name to this specification in the presence of 80 two subscribing witnesses.

ARCHIE J. MURRAY.
